(57) **CLAIM**

The ornamental design for a soccer sock-support patch, as substantially shown and described.

DESCRIPTION

FIG. 1 is a right side elevational view of a soccer sock support patch showing my new design, the undisclosed rear is not part of the claimed design;

FIG. 2 is a right side elevational view of the soccer sock-support patch;

FIG. 3 is a front view of the soccer sock-support patch;

FIG. 4 is a rear view of the soccer sock-support patch; and, FIG. 5 is a left side elevational view of the soccer sock-support patch.

The broken lines are included for the purpose of illustration and form no part of the claimed design.
